CLAIM

The ornamental design for a chest multisensor array, as shown and described.

DESCRIPTION

The inventors intend the term “chest multisensor array” to embrace, *inter alia*, disposable multisensor arrays placed on a patient’s chest for detecting vital signs parameters.

FIG. 1 is a front view of a chest multisensor array showing our new design;

FIG. 2 is a rear view thereof;

FIG. 3 is a bottom view thereof;

FIG. 4 is a top view thereof;

FIG. 5 is a left side view thereof; and,

FIG. 6 is a right side view thereof.

The broken line showing is for illustrative purposes only and forms no part of the claimed design.
